UNITED STATES PATENT OFFICE

149,152

DESIGN FOR A TROLLING REEL

William H. Thompson, Detroit, Mich.

Application June 12, 1946, Serial No. 130,648

Term of patent 3½ years

(Cl. D31—4)

To all whom it may concern:

Be it known that I, William H. Thompson, a citizen of the United States, residing at Detroit, in the county of Wayne and State of Michigan, have invented a new, original, and ornamental Design for a Trolling Reel, of which the following is a specification, reference being had to the accompanying drawing, forming part thereof.

In the drawing

Fig. 1 is a perspective view of a trolling reel, showing my new design;

Fig. 2 is an elevation of the same.

I claim:

The ornamental design for a trolling reel, as shown.

WILLIAM H. THOMPSON.
